(57) **CLAIM**

The ornamental design for a refrigerant compressor for air conditioner of vehicles, as shown and described above.

DESCRIPTION

FIG. 1 is a left side view of a refrigerant compressor for air conditioner of vehicles, according to the design.

FIG. 2 is a top plan view of the refrigerant compressor, as shown in FIG. 1.

FIG. 3 is a front view of the refrigerant compressor, as shown in FIG. 1.

FIG. 4 is a rear view of the refrigerant compressor, as shown in FIG. 1.

FIG. 5 is a right side of the refrigerant compressor, as shown in FIG. 1.

FIG. 6 is a bottom plan view of the refrigerant compressor, as shown in FIG. 1.

FIG. 7 is a front perspective view of the refrigerant compressor, as shown in FIG. 1; and,

FIG. 8 is a rear perspective view of the refrigerant compressor, as shown in FIG. 1.

It being understood that the broken lines are for illustrative purposes only.
